TAIL FORMING DEVICE FOR BOBBIN TWISTER

James M. Elliott, Calgary, Alberta, and James U. Gray, Ottawa, Ontario, Canada, assignors to Courtaulds (Canada) Limited, Ontario, Canada

Filed June 18, 1958, Ser. No. 742,895

22 Claims. (Cl. 57—34)

This invention relates to an improved method of applying a transfer tail or magazine wrap to a bobbin or similar yarn package, and more particularly to applying a transfer tail to individual bobbins without interference with the normal travel and operation of the ring rail and its operating mechanism.

The invention consists essentially in individually raising and lowering the bobbin on which the yarn is to be wrapped in order to bring the bobbin extension on which the transfer tail is to be wrapped, into line with the yarn as it leaves the traveller when the ring rail of the twisting and winding machine is at or approaching the bottom of its travel, without utilizing additional movement of the ring rail or otherwise interfering with the mechanism causing reciprocation of the ring rail or of rotation of the bobbin. The raising of the bobbin in conjunction with suitably placed and designed slots in the bobbin flange directs the yarn from above the bobbin flange on to a special winding core on the underside of the bobbin flange when the ring rail of the twisting and winding machine carries the yarn below the flange of the raised bobbin when the ring rail approaches the lower end of its travel. The bobbins are raised by hand individually by means of a suitable cam device so that the transfer tail can be applied to the bobbin at the beginning of the yarn winding operation without regard to the amount of yarn already wound on other bobbins on the same machine.

It has been the practice in the operation of yarn twisting and winding machines to tie in with the mechanism raising and lowering the ring rail, such additional mechanism as will displace the ring rail a short distance below.

As an essential part of the starting up of the bobbin winding and the formation of a transfer tail it has been found of advantage to direct the running yarn directly to the bobbin and passing it downwardly axially through the bobbin instead of having the yarn by-pass the bobbin as has been the general practice. By this means certain other parts of the twisting and winding machine have been eliminated or simplified, making it easier to carry out the operation of directing the yarn onto the traveller and starting the winding operation, on its normal travel in order to bring the yarn as it leaves the traveller into line with the transfer tail extension of the bobbin. In some cases this operation has been reversed and the transfer tail formed on an extension at the top of the bobbin. Then again various methods have been used to change the position of the yarn guide hook at a stage in the travel of the guide rail in order to bring the yarn into line with the bobbin extension. In all of these methods the mechanism employed is tied in with the ring rail driving mechanism and has to be finely adjusted in order that the timing of the transfer from one part of the bobbin to the other will be just at the right position in relation to the travel of the ring rail. This has been the cause of considerable trouble in maintaining accurate high speed operation of the machines over long periods. Furthermore, because of the nature of the mechanism and its operation, all bobbins on a ring rail have a transfer tail formed

2

at the same time regardless of the amount of yarn already wound on the bobbin, resulting in a considerable waste of yarn and loss of time in the operation of the machine.

In the present invention the wrapping of the transfer tail is accomplished by the machine operator on an individual basis by the lifting of individual bobbins as and when required and not on a group basis tied in with the mechanical operation of the machine.

The primary object of the invention is to provide a simple and easy to operate mechanism whereby the bobbin of a twisting and winding machine can be elevated individually for the purpose of forming a transfer tail.

A further object of the invention is to divorce the operation of forming a transfer tail on a bobbin from the mechanism operating the twisting and winding machine as a whole.

A further object of the invention is to provide a hand operated mechanism for individually elevating a bobbin for the purpose of forming a transfer tail which involve no running mechanism.

A further object of the invention is to provide a simple device whereby the tightly wound transfer tail can be slackened without fouling when the transfer tail is to be unwound.

A further object of the invention is to eliminate the passing of the yarn down along side the bobbin and its driving mechanism preparatory to the starting up of the winding operation.

A further object of the invention is to incorporate within the bobbin carrying spindle, an air ejection system, the yarn inlet of which is situated adjacent the presently situated upper air ejector thereby simplifying the transfer of the running yarn to the bobbin.

A further object of the invention is to effect cutting of the running yarn and commencement of the winding operation from above the ring rail irrespective of the position of the ring rail at start up of rotation of the bobbin.

Other objects of the invention will be apparent from the following description and the drawings which illustrate embodiments of the invention.

Fig. 1 is a front view of a yarn twisting and winding bobbin assembly partly in section to show the bobbin raising means.

Fig. 2 is a side view of the assembly shown in Fig. 1 and showing the bobbin in the raised position.

Fig. 3 is a side view of the lower part of the bobbin partly in section on the line 3—3 of Fig. 4 to show a part of the yarn guiding slot.

Fig. 4 is a bottom view of the bobbin and showing in chain dotted lines the direction of winding of the yarn on the bobbin extension.

Fig. 5 is a side view of the edge of the bobbin flange showing the yarn guiding slot.

Fig. 6 is a section on the line 6—6 of Fig. 4 showing the spring-loaded button about which the transfer tail is looped in the winding operation.

Fig. 7 is a view similar to Fig. 6 but showing the spring-loaded button depressed for ease of unwinding of the transfer tail.

Fig. 8 is a partial diagrammatic view of a standard yarn feeding and winding assembly incorporating the bobbin raising mechanism.

Fig. 9 is a view similar to Fig. 8 but showing a modified system of feeding the yarn to the top of and axially through the bobbin prior to the actual winding operation, the yarn and the top of the bobbin being shown in section so as to show the slot 52.

Fig. 10 is a top view of the bobbin shown in Fig. 9.

Referring to the drawings, the yarn twisting and winding machine has the fixed channel frame 1 and the vertically reciprocating ring rail 2 as essential parts of a

standard machine. The bobbin carrying spindle 3 is provided with a collar 4 and a drive pulley 5 at its lower end. The bobbin carrying spindle 3 is rotatably mounted in the spindle carrier 6 of which the oil dash-pot 7 forms a part. The spindle carrier 6 is mounted on the top flange 8 of the channel frame 1 and is secured thereto by means of the clamp nut 9. The flange 4 of the spindle 3 is provided with a pair of upwardly projecting and oppositely disposed pins 10 for engaging with the winding bobbin 11 when it rests on the top of the flange 4.

Interposed between the spindle carrier 6 and the hollow drive pulley 5 is a sleeve 12 whose bottom flange 13 faces the bottom flange 14 of the pulley 5.

The bobbin 11 may be of any suitable shape to take the yarn and is here shown as having a parallel sided body portion 15 and a flared top portion 16. A wide flange 17 provides the bottom support for wound-on yarn and is only slightly smaller in diameter than the ring 18 mounted on the ring rail 2. The edge 19 of the flange 17 is slightly rounded to provide a smooth surface for the yarn as it is fed from above the flange to below the flange and from the rounded edge the under surface of the flange is tapered inwardly at approximately 45° at 20 and is then tapered inwardly sharply at 21 to meet the undercut tail receiving ring 22. The tail receiving ring 22 is undercut at approximately 30° from the vertical and its under surface 23 forms a bearing flange to rest on the top surface of the carrying spindle collar 4. The bearing flange 23 is provided with two apertures 24 adapted to receive the pins 10 of the flange 4 to effect rotation of the bobbin 11 as the drive pulley 5 is rotated.

Under normal operation of winding the yarn on the bobbin 11, when the rail 2 is at the bottom of its stroke, the top edge of the ring 18 is level with the top surface of the flange 17. In order that a transfer tail of yarn may be formed on the ring 22, the bobbin 11 is lifted up for a short distance. This is accomplished by means of the manually operated rod 25 which passes through apertures in the top and bottom flanges 8 and 26 of the channel frame 1. The top end of the rod 25 contacts the underside of the flange 13 of the sleeve 12 while the bottom end of the rod 25 rests on the edge of the cam 27. The cam 27 is mounted on the shaft 28 which is supported on the bracket 29 mounted on the underside of the flange 26. A handle 28a fixed to the shaft 28 is manipulated to effect rotation of the cam and lifting of the rod 25 and with it the sleeve 12 and spindle 3. As the spindle 3 is lifted, the flange 17 is carried above the top edge of the ring 18 to bring the yarn tail receiving ring 22 into line with the ring 18.

Set in the underside of the flange 17 is the transfer tail carrying button 30 which together with the ring 22 carries the transfer tail 31 in the form of a loop wound about the ring 22 and the button 30 as shown in Fig. 4 of the drawings. The button 30 is held by its flange 32 in the sleeve 33 which is pressed into and bonded in the recess 34 of the flange 17. The button 30 is shouldered at 35 to form a reduced head 36 and is hollow formed to receive the spring 37. The spring 37 holds the large diameter button 30 in line with the recessed portion of the ring 22 and as the transfer tail is being formed it automatically winds on both the ring 22 and button 30 under tension.

In order to transfer the yarn "Y" from the ring 18 onto the ring 22 and button 30 the edge of the flange 17 is notched. The notching of the flange is in the form of a double V as seen in Figs. 3, 4 and 5 of the drawings. The angled surface 42 provides the lead in for the yarn into the notch 40 for the transfer tail forming, while the other V notch 41 is the lead out from the transfer tail forming. Should a portion of the yarn first be wound in the bobbin 11 above the flange and the bobbin be moved up as the ring rail 2 is approaching the bottom of its downward stroke, the yarn Y will be draped on the edge 19 of the flange 17. As the notches 40 and 41 come

round to the yarn, the yarn will fall into the notch 40 and thence be pulled around one side of the ring 22, the button 30 and back on to the ring 22 to form a looped transfer tail 31. The looping of the yarn will be continued until the ring rail 2 starts its upward travel and the bobbin is lowered. As the top edge of the ring 18 comes above the top surface of the flange 17, the yarn Y will ride into the V 41 and be carried from there over the top surface of the flange 17 back onto the body 15 of the bobbin 11. A blind hole 38 is drilled on the underside of the flange and is centered on the line of yarn as it passes from the notch 40 onto the transfer tail forming ring 22. This blind hole 38 facilitates the cutting of the yarn at this point when the transfer tail is to be tied to the tail of another bobbin.

While the bobbin 11 is at rest with no yarn being wound onto it, the continuously running yarn "Y" coming off the drying rolls 43 is, in a standard machine, fed through the ring 18 and through a slot 44 in the edge of the bobbin flange 17 and thence into the air ejector 45 and through the pipe 46 leading to the waste yarn collector box. The air ejector being fed air through the pipe 47 from the main header 48 and controlled by the valve 53. This is standard procedure and is shown in semi-diagrammatic form in Fig. 8 of the drawings. As soon as the spindle brake, not shown, is released and the bobbin starts to rotate, the slot 44 carries with it the yarn "Y" thereby exerting a side pressure of the yarn "Y" against the knife blade which is assembled as part of the air ejector unit 45 thereby cutting the yarn and allowing it to be wrapped on the rotating bobbin. There is a certain amount of difficulty in transferring the yarn from the upper air ejector unit 49, to the air ejector unit 45 as it is apt to be cut against either the upper edge of the bobbin or the bobbin flange and thereby fouling up around the bobbin and the traversing ring rail 2. In order to avoid this difficulty, the yarn "Y" is taken from the upper air ejector 49 and transferred directly to an air ejector pipe 50 which is a permanent fixture axially set in the bobbin spindle 3 as shown in Fig. 9 of the drawings. This air ejector pipe 50 passes down through the oil dash-pot 7 and into the air ejector unit 51 and thence to the waste yarn collector box. The pipe 50 is permanently sealed by welding or other suitable means at the lower end of the oil dash-pot 7 in order to prevent leakage of the oil. At the start the yarn "Y" from the dryer drum 43 is being fed to the upper air ejector 49. It is taken from this air ejector and transferred down one side of the bar 54 which straddles the top of bobbin 11 directly to an air ejector pipe 50 in the bobbin spindle 3. This is shown in Figure 9. The yarn passes to that side of the bar which contains the slot 52. While continuing to be fed into pipe 50 the yarn is pushed sideways by the operator into the slot 52 and thence sideways and downwards over the top edge of the bobbin to engage the traveller on the traversing ring rail 18. The path of the yarn "Y" is now from the dryer drum 43 to the ring rail 18 over the upper edge of the bobbin 11, through the slot 52 to the pipe 50. The spindle brake is released so that the bobbin starts to rotate. The yarn "Y" begins to be wound on to the bobbin and at the same time the side pressure exerted causes it to be cut on the top edge of pipe 50. The fact that the yarn is kept entirely above the bobbin flange during the starting operation ensures that any pile up of yarn, caused by failure to properly thread the yarn in the ring 18, can be cleared away promptly without fouling up the drive mechanism below, and the yarn can be promptly transferred from the top of the pipe 50 to the upper air ejector unit 49 while restarting of the winding operation is carried out.

From the above described method and apparatus for winding yarn on bobbins on a twisting and winding machine, it will be noted that a considerable amount of mechanism, particularly mechanism which has to be driven in synchronized adjustment with the main drive of the

machine, has been eliminated. In particular all the mechanism which, in the past, had had to be incorporated in some form or another with the reciprocating drive of the ring rail 2, to give the desired extra travel of the ring rail, has been eliminated. With the present invention it is no longer necessary to give an added length of travel to the ring rail in order to form a transfer tail, but in place thereof there is added a simple hand operated mechanism which elevates each bobbin assembly on an individual basis. By this means it is possible to institute the formation of the transfer tail as soon as an individual bobbin is set rotating. Whereas in the older method all the bobbin assemblies served by one ring rail had to be serviced and a considerable amount of yarn was wrapped on some bobbins before the last one was set up and the ring rail given the extra travel necessary to form the transfer tail which was formed at the same time on all bobbins served by the one ring rail. In the present case the ring rail has a fixed traverse and does not control in any way the timing of the formation of the transfer tail. This individual raising of the bobbins combined with the simplified method of directing the yarn from the drying rolls to the top of the bobbin rather than to the side of and below the bobbins, protects the yarn during the bobbin set up period, makes it easier to handle and provides a more uniform wound bobbin. The fact that the transfer tail is formed uniformly on all bobbins ensures that on the unwinding operation a uniform footage from each bobbin will be obtained.

The unique method of forming the transfer tail in a loop ensures that the tail will be kept under tension at all times until the bobbin is ready for rewinding when a single strand can be readily cut and the button depressed to release freely the whole transfer tail in the form of a hank, ensures that the tying of the transfer tail to the end of yarn of another bobbin can be done in a clean and efficient manner.

What we claim is:

1. In a yarn twisting and winding machine having one or more bobbin spindles and in which the ring rail of the machine is restricted to a normal vertical reciprocating yarn winding travel, means to individually raise the bobbins on their spindles to effect the formation of a transfer tail on the bobbin.

2. In a yarn twisting and winding machine having one or more bobbin spindles and in which the ring rail of the machine is restricted to a normal vertical reciprocating yarn winding travel, means to direct the running yarn axially through said spindles and from the top of said spindles onto the rotating bobbins, and means to individually raise the bobbins on their spindles to effect the formation of a transfer tail on the bobbin.

3. In a yarn twisting and winding machine having one or more bobbin spindles and in which the ring rail is restricted to a normal vertical reciprocating yarn winding travel, manual means to individually raise the bobbins on their spindles to effect the formation of a transfer tail on the bobbin.

4. In a yarn twisting and winding machine having one or more bobbin spindles and in which the ring rail is restricted to a normal vertical reciprocating yarn winding travel, manual means to individually raise the bobbins on their spindles for a short distance when the ring rail is approaching the bottom of its downward travel to effect the formation of a transfer tail on the bobbin.

5. In a yarn twisting and winding machine having one or more bobbin spindles and in which the ring rail is restricted to a normal vertical reciprocating yarn winding travel, a bobbin on each of said spindles, said bobbin having a yarn supporting flange and a transfer tail forming ring immediately thereunder, manual means to individually raise the bobbins on their spindles for a short distance to bring the transfer tail forming ring into line with the ring rail when the ring rail is approaching the

bottom of its downward travel to effect the formation of a transfer tail.

6. In a yarn twisting and winding machine having one or more bobbin spindles and in which the ring rail is restricted to a normal vertical reciprocating yarn winding travel, a bobbin on each of said spindles, said bobbin having a yarn supporting flange, a transfer tail ring immediately thereunder, a button projecting downwardly from the underside of said flange, said button being disposed at a radius from the axis of the bobbin, manual means to individually raise the bobbins on their spindles for a short distance to bring said transfer tail ring and button into line with the ring rail when the ring rail is approaching the bottom of its downward travel to effect the formation of a transfer tail loop about said transfer tail ring and button.

7. In a yarn twisting and winding machine as set forth in claim 6, wherein the button on the underside of the flange is spring-loaded to allow depression of the button for quick release of the transfer tail loop.

8. In a yarn twisting and winding machine as set forth in claim 6, wherein the button on the underside of the flange is spring-loaded and is provided with a large diameter section about which in conjunction with the transfer tail ring, the transfer tail loop is initially formed, and a smaller diameter section onto which the transfer tail loop is transferred when the button is depressed.

9. In a yarn twisting and winding machine having one or more bobbin spindles and in which the ring rail is restricted to a normal vertical reciprocating yarn winding travel, a bobbin on each of said spindles, said bobbins having a yarn supporting flange and a transfer tail forming ring immediately thereunder, spindle raising means including a rod, a cam under the lower end of said rod, and manual means to rotate said cam and raise said rod and with it said spindle and bobbin to bring said transfer tail ring into line with the ring rail when the ring rail is approaching the bottom of its downward travel to effect the formation of a transfer tail on the transfer tail ring.

10. In a yarn twisting and winding machine having one or more bobbin spindles and in which the ring rail is restricted to a normal vertical reciprocating yarn winding travel, a bobbin on each of said spindles, said bobbins having a yarn supporting flange, a transfer tail ring immediately thereunder, a spring-loaded button projecting downwardly from the underside of said flange, said button being disposed at a radius from the axis of the bobbin, spindle and bobbin raising means including a rod, a cam under the lower end of said rod, and means to rotate said cam and raise said rod and with it said spindle and bobbin to bring said transfer tail ring and button into line with the ring rail when the ring rail is approaching the bottom of its downward travel to effect the formation of a transfer tail loop about said transfer tail ring and button.

11. In a yarn twisting and winding machine having one or more bobbin spindles and in which the ring rail is restricted to a normal vertical reciprocating yarn winding travel, a bobbin on each of said spindles, said bobbin having a yarn supporting flange, a transfer tail ring immediately thereunder, a spring-loaded button projecting downwardly from the underside of said flange, said button being disposed at a radius from the axis of the bobbin and having a large diameter section about which, in conjunction with the transfer tail ring, a transfer tail loop is formed, and a smaller diameter section onto which the transfer tail loop is transferred when the button is depressed, a spindle and bobbin raising means including a rod, a cam under the lower end of said rod, and means to rotate said cam and raise said rod and with it said spindle and bobbin to bring said transfer tail ring and the large diameter section of said button into line with the ring rail when the ring rail is approaching the bottom of its downward travel to effect the formation of a transfer tail loop about said transfer tail ring and button.

12. In a yarn twisting and winding machine having one or more bobbin spindles and in which the ring rail is restricted to a normal vertical reciprocating yarn winding travel, a bobbin on each of said spindles, said bobbin having a yarn supporting flange and a transfer tail forming ring immediately thereunder, manual means to individually raise the bobbins on their spindles for a short distance to bring the transfer tail forming ring into line with the ring rail when the ring rail is approaching the

12. In a yarn twisting and winding machine having one or more bobbin spindles and in which the ring rail including the yarn traveller is restricted to a normal vertical reciprocating yarn winding travel, a bobbin on each of said spindles, said bobbin having a yarn supporting flange, a double V notch on the edge of said flange, a transfer tail ring immediately below said flange, a spring loaded button projecting downwardly from the underside of said flange, said button being disposed at a radius from the axis of the bobbin and having a large diameter section about which, in conjunction with the transfer tail ring, a transfer tail loop is formed, and a smaller diameter section onto which the transfer tail loop is transferred when the button is depressed, a spindle and bobbin raising means including a rod, a cam under the lower end of said rod, and manual means to rotate said cam and raise said rod and with it said spindle and bobbin to bring said transfer tail ring and the large diameter section of said button into line with the ring rail, one of the V notches of the flange catching and guiding the yarn from the yarn traveller on the ring rail onto the transfer tail ring and about said button to form a transfer tail loop, the other of said V notches catching and guiding the yarn from the transfer tail loop to above said flange when the ring rail moves upwards beyond said flange.

13. In a yarn twisting and winding machine having one or more bobbin spindles and in which the ring rail including the yarn traveller is restricted to a normal vertical reciprocating yarn winding travel, a bobbin on each of said spindles, means to direct the yarn axially downwards through said bobbin, means to hold said yarn to the top of the bobbin and to cut said yarn when the bobbin is rotated, said bobbin having a yarn supporting flange, a double V notch on the edge of said flange, a transfer tail ring located immediately below said flange, a spring-loaded button projecting downwardly from the underside of said flange, said button being disposed at a radius from the axis of the bobbin and having a large diameter section about which, in conjunction with the transfer tail ring, a transfer tail loop is formed, and a smaller diameter section onto which the transfer tail loop is transferred when the spring-loaded button is depressed, a spindle and bobbin raising means including a rod, a cam under the lower end of said rod, and means to rotate said cam and raise said rod and with it said spindle and bobbin to bring said transfer tail ring and the large diameter section of said button into line with the ring rail, one of the V notches of the flange catching and guiding the yarn from the yarn traveller on the ring rail onto the transfer tail ring, and about said button to form a transfer tail loop, the other of said V notches catching and guiding the yarn from the transfer tail loop to above said flange when the ring rail moves upwards beyond said flange.

14. In a yarn twisting and winding machine having one or more bobbin spindles and in which the ring rail including the yarn traveller is restricted to a normal vertical reciprocating yarn winding travel, an air ejection passage through said spindles, a bobbin on each of said spindles, a yarn engaging slot in the top of said bobbins adapted to hold and cut the yarn passing from the yarn traveller through said air ejection passage when the bobbin is first rotated, said bobbin having a yarn supporting flange, a double V notch on the edge of said flange, a transfer tail ring located immediately below said flange, a spring loaded button projecting downwardly from the underside of said flange, said button being disposed at a radius from the axis of the bobbin and having a large diameter section about which, in conjunction with the transfer tail ring, a transfer tail loop is formed, and a smaller diameter section onto which the transfer tail loop is transferred when the spring loaded button is depressed, a spindle and bobbin raising means including a rod, a cam under the lower end of said rod, and means to rotate said cam and raise said rod and with it said spindle and bobbin to bring said transfer tail ring and the large

diameter section of said button into line with the ring rail and yarn traveller, one of the V notches of the flange catching and guiding the yarn from the yarn traveller on the ring rail on to the transfer tail ring and about said button to form a transfer tail loop, the other of said V notches catching and guiding the yarn from the transfer tail loop to above said flange for normal winding when the ring rail moves upwards beyond said flange.

15. In a yarn twisting and winding machine in which the yarn is taken from drying rolls and wound onto a rotating bobbin and is guided thereon by a yarn traveller on a vertically reciprocating ring rail, a bobbin carrying spindle, a bobbin mounted on said spindle, an air ejection system axially mounted in said spindle and having its yarn receiving opening located near the top level of said bobbin, yarn engaging means on the top of said bobbin adapted to hold and cut the yarn at the mouth of the air ejection system when the bobbin is rotated, means to raise said bobbin a short distances and means on said bobbin adapted to engage the yarn between the top of said bobbin and the yarn traveller to form a separate yarn transfer tail on the lower end of said bobbin when the bobbin has been raised as the ring rail approaches the lower end of its travel.

16. A bobbin for use on a yarn twisting and winding machine, comprising a hollow body portion, a flange projecting from said body portion in a plane at right angles to the axis of the bobbin and located near the lower end of said body portion, yarn transfer tail loop receiving members on the underside of said flange comprising an axially disposed recessed ring portion and a spring loaded button disposed at a radius from the axis of the bobbin and substantially in the same plane as the recessed ring portion, said spring loaded button being depressable into the said flange in an axis parallel with the axis of the bobbin, a V notch on the edge of said flange adapted to guide the yarn onto said transfer tail forming members to form a loop thereabout, and a second V notch on the edge of said flange adapted to guide the yarn away from said loop receiving members.

17. A bobbin for use on a yarn twisting and winding machine comprising a hollow body portion, a flange projecting from said body portion in a plane at right angles to the axis of the bobbin and located near the lower end of said body portion, yarn transfer tail loop receiving members on the under side of said flange comprising an axially disposed recessed ring portion and a spring loaded button disposed at a radius from the axis of the bobbin and substantially in the same plane as the recessed ring portion, said spring loaded button having a large diameter body section and a smaller diameter body section and being depressable into the said flange in an axis parallel with the axis of the bobbin, a V notch on the edge of said flange adapted to guide the yarn onto the recessed ring portion and the large diameter body section of the spring loaded button, and a second V notch on the edge of said flange adapted to guide the yarn away from said loop receiving members.

18. A bobbin for use on a yarn twisting and winding machine comprising a hollow body portion, a flange projecting from said body portion in a plane at right angles to the axis of the bobbin and located near the lower end of said body portion, said flange having its edge angled inwardly on its underside to provide a smooth yarn guiding surface, yarn transfer tail loop receiving members on the underside of said flange comprising an axially disposed recessed ring portion and a spring loaded button disposed at a radius from the axis of the bobbin and substantially in the same plane as the recessed ring portion, said spring loaded button having a large diameter body section and a smaller diameter body section and being depressable into said flange in an axis parallel with the axis of the bobbin, a V notch on the edge of said flange and extending down and inwardly to the depth

of the angled surface of the flange edge, said notch adapted to guide the yarn onto the recessed ring portion and the large diameter body section of the spring loaded button, and a second V notch on the edge of said flange, said second notch having a relatively long peripheral side and extending slightly beyond the inner lower edge of the angled surface of the flange edge, and adapted to guide the yarn away from said loop receiving members.

19. A bobbin for use on a yarn twisting and winding machine comprising a hollow body portion, a flange projecting from said body portion in a plane at right angles to the axis of the bobbin and located near the lower end of said body portion, said flange having its edge angled inwardly on its underside to provide a smooth yarn guiding surface, yarn transfer tail loop receiving members on the underside of said flange comprising an axially disposed recessed ring portion and a spring loaded button disposed at a radius from the axis of the bobbin and substantially in the same plane as the recessed ring portion, said spring loaded button having a large diameter body section and a smaller diameter body section and being depressable into said flange in an axis parallel with the axis of the bobbin, an air ejection system axially mounted on the spindle and having its yarn receiving opening located near the top level of the bobbin, a bar straddling the top end of said hollow body portion, a yarn end holding slot in said bar, a V notch on the edge of said flange and extending down and inwardly to the depth of the angled surface of the flange edge, said notch adapted to guide the yarn onto the recessed ring portion and the large diameter body section of the spring loaded button, and a second V notch on the edge of said flange, said second notch having a relatively long peripheral side and extending slightly beyond the inner lower edge of

the angled surface of the flange edge and adapted to guide the yarn away from said loop receiving members.

20. A bobbin for use on a yarn twisting and winding machine as set forth in claim 18, in which the relatively long peripheral edge of the second V notch extends inwardly to the depth of the first mentioned V notch on the top surface of the flange.

21. A bobbin for use on a yarn twisting and winding machine as set forth in claim 19 in which the relatively long peripheral edge of the second V notch extends inwardly to the depth of the first mentioned V notch on the top surface of the flange.

22. A bobbin for use on a yarn twisting and winding machine comprising a hollow body portion having its upper portion flared outwardly, a bar straddling the top end of said flared portion of the body, a yarn end holding slot in said bar, a flange projecting from the lower end of said body portion, yarn transfer tail loop receiving members on the underside of said flange said transfer tail loop receiving members comprising an axially disposed recessed ring and a spring loaded button disposed at a radius from the axis of the bobbin, and a pair of V notches on the edge of said flange adapted to guide the yarn in loop form onto and away from said recessed ring and spring loaded button.
